US00D999450S

(12) United States Design Patent (10) Patent No.: US D999,450 S
(45) Date of Patent: * Sep. 19, 2023

(54) ADJUSTABLE RUBBER HEADBAND

(71) Applicant: Mor Medina, Ariel (IL)

(72) Inventor: Mor Medina, Ariel (IL)

() Term: 15 Years

(21) Appl. No.: 35/513,649

(22) Filed: Sep. 29, 2021

(80) Hague Agreement Data

Int. Filing Date: Sep. 29, 2021

Int. Reg. No.: DM/218825

Int. Reg. Date: Sep. 29, 2021

Int. Reg. Pub. Date: Feb. 18, 2022

(51) LOC (14) Cl. 02-03

(52) U.S. Cl.

USPC D28/41; D2/865

(58) Field of Classification Search

(57) CLAIM

The ornamental design for an adjustable rubber headband, as shown and described.

DESCRIPTION

1. Adjustable rubber headband

1.1 : Top

1.2 : Bottom

1.3 : Right

1.4 : Left

1.5 : Front

1.6 : Back

1.7 : Perspective

1.8 : Perspective

1.9 : Perspective

1.10 : Perspective

The long dash-dash broken lines defining the outer perimeter edge and the rectangle along the fastener of the adjustable rubber headband depict features of the adjustable rubber headband that form no part of the claimed design. The dot-dash broken lines depict claimed seam lines.

1 Claim, 10 Drawing Sheets
